Primary Examiner—James R. Largen**Attorney, Agent, or Firm—Stroock & Stroock & Lavan****[57] CLAIM**

The ornamental design for a bathtub rim, as shown and described.

DESCRIPTION

FIG. 1 is a perspective view, taken from the top, front and right side of a bathtub rim showing my new design; FIG. 2 is a top plan view thereof; FIG. 3 is a right side elevational view thereof; FIG. 4 is a rear elevational view thereof; FIG. 5 is a bottom plan view thereof; and, FIG. 6 is an enlarged sectional view taken along line 6—6 of FIG. 1.

The broken line representation of a bathtub in FIGS. 1 through 5 is for purposes of illustration only and forms no part of the claimed design.

FIG. 1

FIG. 6
